UNITED STATES PATENT OFFICE.

HIRAM G. WILSON, OF ST. LOUIS, MISSOURI, ASSIGNOR TO THE WILSON CAR WARMING AND VENTILATING COMPANY, OF EAST ST. LOUIS, ILLINOIS.

CAR-HEATER.

SPECIFICATION forming part of Letters Patent No. 372,779, dated November 8, 1887.

Application filed January 30, 1886. Serial No. 190,370. (No model.)

To all whom it may concern:

Be it known that I, HIRAM G. WILSON, of the city of St. Louis and State of Missouri, have invented a new and useful Improvement 5 in Heaters for Cars and other Vehicles while in Motion, of which the following is a specification.

My invention relates to the heating of cars, but is adapted also to the heating of other 10 compartments.

The object of the invention is to provide for the warming of the floor of the car or other compartment, and to furnish a steady warm temperature throughout the car, the heat being diffused in all parts. The ordinary way 15 of heating cars by exposed pipes has a well-known objection of unequal heating, making the heat too great in one place and too little in another. Attempts have been made here- 20 tofore to remedy this difficulty; but, so far as I am aware, the devices suggested have never come into use. These have consisted of various devices for distributing hot air through the floor of the car, and in some cases products 25 of combustion have been passed into the air-chamber underneath the floor of the car and about its sides.

My invention consists in the special construction, as hereinafter described. I use ordinary heating-pipes to conduct the products 30 of combustion, or any heating medium, and arrange them on the floor of the car or other vehicle. These pipes may be two inches in diameter, (more or less.) They are laid directly on the floor of the car, and are covered 35 with any suitable material to form a floor, the floor having supports under it to form an air-chamber, and the floor last named—that is, the upper floor—is perforated throughout its 40 entire surface with holes one-quarter of an inch, or thereabout, in diameter, as shown in Figures 2 and 3. The floor may be covered with carpet or matting, as may be desired. This 45 will not interfere with the distribution of air. The heater may conveniently consist of a base-burner stove with up and down drafts, and this may be incased with asbestos or any suitable material to prevent radiation outward from the point of combustion, and the maga-

zine may be placed at any point inside or outside of the car. 50

As hereinafter described, I contemplate adding this floor to cars already in use, or to cars built for the purpose, as a temporary or removable floor over the ordinary floor, and 55 when this temporary floor, with the heating-pipes, is in place the seats of the cars may be raised by the addition of an extra cushion. As above intimated, this same arrangement of devices may be applied to a room of a 60 building.

The precise construction of my invention is shown in the accompanying drawings, in which—

Fig. 1 represents a plan of the floor; Fig. 65 2 a transverse section, Fig. 3 a longitudinal section, and Fig. 4 an inverted plan, thereof. In the drawings the permanent floor is represented at C, and is the floor of the car or other equivalent structure of the ordinary 70 form. On this floor is laid a series of supports, B. These consist of short pieces of scantling or other similar material. They are arranged in interrupted or broken lines, as shown in the figures, so that they nowhere 75 form a closed space, but leave a free circulation of air possible throughout the chamber between the upper and lower floors. The upper or temporary floor is preferably made in sections of about three to five feet, of any suitable flooring material, and these sections are preferably attached to the supports B, so that the sections or the supports can be laid down or taken up together. The temporary floor is 80 perforated throughout its entire surface with 85 holes to allow the passage of air from the heating-chamber below up into the space above. The air-chamber between the upper and lower floors is heated by the flues or pipes D, which pass lengthwise through the floors from the 90 heater, extending through the supports and being exposed to the air within the heating-chamber, so that the air is heated by contact with these pipes.

I am aware that various plans have been 95 heretofore devised for heating cars or like structures, and that an air-chamber beneath the floor of the car, through which the pro-

ducts of combustion from a lamp or other heater are passed, is not new, and I do not broadly claim such a structure.

I claim as my invention—
5 A heating-chamber consisting of a temporary perforated floor laid upon supports B, placed on and combined with the permanent or lower floor and arranged in broken or in-

terrupted lines to allow circulation of air, and heating-pipes D, running through this air-chamber between the upper and lower floors, substantially as described.

HIRAM G. WILSON.
